UNITED STATES PATENT OFFICE.

WILLIAM DAMEREL, OF BROOKLYN, NEW YORK.

CANDLE-LAMP.

SPECIFICATION forming part of Letters Patent No. 335,020, dated January 26, 1886.

Application filed May 21, 1885. Serial No. 166,288. (No model.)

To all whom it may concern:

Be it known that I, WILLIAM DAMEREL, a citizen of the United States, residing at Brooklyn, in the county of Kings and State of New York, have invented new and useful Improvements in Candle-Lamps, of which the following is a specification.

This invention has for its object to provide an improved candle holder or lamp; and it consists in the novel combination of devices hereinafter described and claimed, reference being made to the accompanying drawings, illustrating my invention, in which—

Figure 1 is a central vertical section of my improved candle-lamp. Fig. 2 is a transverse horizontal section in the plane $\alpha\alpha$, Fig. 1. Fig. 3 is a similar section in the plane yy , Fig. 1.

Similar letters indicate corresponding parts.

In the drawings the letter A designates what I shall term the "wastage-receiver," which is preferably made of glass, and consists of an annular cup-shaped body, a, having a gutter, b, and to the bottom of this receiver is secured by any convenient means an annular disk, B, made of rubber or similar elastic material. In the example shown in the drawings the latter is secured to the receiver by means of an annular disk or washer, C, of some rigid material, which is placed over the elastic disk, and by the hooks e, which pass through the disk, and then upward, their lower ends being provided with flat heads, while their upper ends are bent downward over the upper edge of the body a of the wastage-receiver, the main part of the hooks being within grooves or indentations d, Fig. 1, in the said body. This wastage-receiver can be secured directly to the candle-socket or hollow shaft D; but I prefer to removably secure the same in the cup-shaped support D', which is likewise provided with an elastic disk, E, which is secured to its bottom by means of wires e, or in any other suitable manner. The wastage-receiver is held in this support by its elastic disk B, the diameter of which is somewhat greater than that of the body of the receiver, and which consequently wedges itself into the support, since the diameter of the latter is the same as that of the body of the receiver.

In the example shown in the drawings the hollow shaft D is split or formed in two longitudinal halves, and is secured to a suitable

base, F, by means of a key, G, in order that the entire device can be separated when so desired.

In order that the hollow shaft shall be rigidly fastened and not shake, I interpose a washer, H, between the key and the base, which lies in a recess or depression formed in the base, while a head, f, is formed near the end of the hollow shaft, which bears on the upper surface of the base, so that by driving in the key firmly a perfectly-rigid connection is obtained.

The candle I, when introduced into the candle-socket, is held by the elastic disks B E, and in order to secure it at some distance below these disks I employ spring-arms J, Fig. 1, which are secured to the said shaft, and in the example shown in the drawings they consist of wires, which are looped through holes arranged on the circumference of the shaft, their ends extending into the interior of the same and clamping the candle.

The object of my invention is to produce a candle-holder or candle-lamp in which the height of the candle can be easily adjusted, and one which prevents the melted stearine, wax, or tallow from dropping on the floor. All the melted stearine flows directly into the annular space of the wastage-receiver, the walls of said space being somewhat flaring, in order that the wastage may reunite and be consumed with the candle. The shaft, instead of being made of sheet metal, can be made of wire rods or other open-work.

What I claim as new, and desire to secure by Letters Patent, is—

1. The combination, substantially as herein-before described, of an annular wastage-receiver, an elastic annular disk secured to the under side of said receiver, and a hollow shaft for receiving a candle.

2. The combination, substantially as herein-before described, of a hollow shaft, a cup-shaped support attached to the upper end of said shaft, an annular wastage-receiver inserted in said support, and annular elastic disks intermediate the receiver and support.

3. The combination, substantially as herein-before described, of an annular wastage-receiver, a cup-shaped support for said receiver, intermediate annular elastic disks, and a hollow candle-shaft having internal spring-arms.

4. The combination, substantially as hereinbefore described, of the hollow shaft, the cup-shaped support secured thereto, the annular wastage-receiver fitting the cup-shaped support, the elastic disk formed in said support, and the base.

5. The combination, substantially as hereinbefore described, of the split hollow shaft, the cup-shaped support for receiving and retaining the upper ends of the shaft-sections, the annular wastage-receiver fitting the cup-shaped support, the elastic disk, the base for receiving the lower ends of the shaft-sections, and the key for securing the shaft-sections to the base.

15 6. A wastage-receiver for candle-lamps, con-

sisting of an annular cup-shaped body, *a*, having an external trough, *b*, and formed with a deep tapering orifice extending entirely through it, and provided at its lower end with 20 an elastic disk, said body receiving the wastage and directing it to the body of the candle, to unite and be consumed therewith, substantially as and for the purpose described.

In testimony whereof I have hereunto set 25 my hand and seal in the presence of two subscribing witnesses.

WILLIAM DAMEREL. [L. S.]
